(57) **CLAIM**

The ornamental design for an airway connector, as shown and described.

DESCRIPTION

FIG. 1 is a perspective view of an airway connector showing our new design;

FIG. 2 is a right side view thereof, the left side being a mirror image thereof;

FIG. 3 is a front view thereof;

FIG. 4 is a back view thereof;

FIG. 5 is a top view thereof;

FIG. 6 is a bottom side view thereof; and,

FIG. 7 is a cross-sectional view taken along line 7-7 of FIG. 3.

The broken lines in the drawings depict portions of the airway connector that form no part of the claimed design.

1 Claim, 4 Drawing Sheets
